(57) CLAIM

The ornamental design for a crescent nail applique, as shown and described herein.

DESCRIPTION

FIG. 1. Is a top perspective view of my new crescent nail applique, the phantom lines showing the finger being for illustrative purposes only and forming no part of the claimed design;

FIG. 2. Is a top plan view thereof;

FIG. 3. Is a bottom plan view thereof;

FIG. 4. Is a right side elevational view thereof;

FIG. 5. Is a left side elevational view thereof;

FIG. 6. Is a front elevational view thereof; and,

FIG. 7. Is a back elevational view thereof.
